[57] CLAIM

The ornamental design for a cosmetic applicator, as shown and described.

DESCRIPTION

FIG. 1 is a left side elevational view of a cosmetic applicator showing my new design with the applicator tip rotated 90° from the vertical;

FIG. 2 is a front elevational view thereof;

FIG. 3 is a rear elevational view thereof;

FIG. 4 is a top plan view thereof;

FIG. 5 is a bottom plan view thereof;

FIG. 6 is a top plan view of a cosmetic applicator showing a modified form of my new design employing a different applicator tip; and

FIG. 7 is top plan view of a cosmetic applicator showing another modified form of my new design with a third embodiment of the tip.

FIG. 1.

FIG. 2.

FIG. 3.

FIG. 4.

FIG. 5.

FIG. 6.

FIG. 7.
